UTILIZATION OF HEAT IN VAPORIZED
FUEL BURNERS

Keith Parr, Preston, Victoria, Australia

Application September 15, 1950, Serial No. 184,940
In Australia September 21, 1949

6 Claims. (Cl. 158—53)

1

This invention relates to vaporized oil fuel burning apparatus of the kind particularly suitable for domestic and industrial heating purposes and in which hydro-carbon fuel, particularly the type generally known as kerosene or as paraffin, is fed by pressure from a supply tank through a heated vaporizing section of the fuel vapor supply tube which terminates in a jet discharge orifice through which the fuel is discharged in vapor form for ignition of the fuel vapor after issuance from the jet orifice.

The invention is particularly useful in the type of oil fuel apparatus wherein the fuel is fed under low pressure to the fuel vapor discharge jet by gravity from an elevated fuel supply tank.

Usually in this class of burner a pre-heating bowl is situated below the vaporizing section of the fuel vapor supply tube for containing methylated spirits or the like which is ignited for heating the fuel vaporizing section of the vapor supply tube and the jet to initiate vaporization of the fuel. Heat supplied by ignition of the fuel vapor after issuance from the vapor jet discharge orifice continues the vaporization of the oil fuel after exhaustion of the methylated spirits in the pre-heating bowl.

Generally in such fuel burners there is a considerable roaring noise created when the fuel is ignited on or around the gas spreading saucer which is situated usually at a selected distance from the jet orifice, to provide for a correct proportion of air to be mixed with the vaporized fuel before ignition of the fuel takes place.

Furthermore, this method of burning oil fuel is comparatively trouble free in operation but is unsuitable for domestic and like use owing to the roaring noise created upon ignition of the fuel and air gas.

Previously known or similar oil fuel burning apparatus wherein a means of silencing the roaring noise is employed, whilst still maintaining proper combustion of the fuel, usually suffer from the disadvantage of becoming overheated under severe conditions of burning such as metal melting or hot-plate stove cooking. This overheating of the means of silencing the fuel gas ignition can cause the fuel gas mixture to ignite inside of the silencer apparatus causing faulty combustion, soot and smell, and sometimes results in portions of the silencer apparatus being melted away and thereby rendering the burner unsuitable for further use. Usually, this means of silencing fuel gas ignition consists of a gas spreading chamber adapted to

2

spread or extend the ignition point of the fuel gas to effect silencing, and usually a restriction or restrictions are provided at the gas ignition point to increase or accelerate the velocity of the fuel gas for the purpose of preventing ignition of the gas in or through the said gas spreading chamber.

This method of silencing however is usually not effective when used under extremely hot conditions of burning or when a low pressure delivery of gas is employed, as the gas is inclined to ignite in the areas of the gas spreading chamber where a lesser velocity in the flow of gas is caused by the restriction or restrictions referred to.

The primary object of the present invention is to provide in oil fuel vapor burners of the class described, a means of reducing to a minimum the noise created upon ignition of the fuel gas, whilst maintaining proper combustion of the fuel, when the burner is operated under normal or severe conditions of burning.

Another object of the invention is to provide in such an improved burner, a means of preventing overheating of the burner silencer and of the gases passing therethrough, by insulation of the portions of the burner silencer exposed to radiation of heat from the burner flame.

A further object of the invention is to provide for use in pressure fed fuel vapor burners, a burner silencer which produces an unbroken line of flame at the ignition point of the fuel gas, which is easily cleanable, and in which burner silencer the fuel gas and flame may be directed upwards from the said burner silencer, thereby adding to the efficiency of the burner.

A still further object of the invention is to provide in such a burner silencer, a gas spreading and directing passage which is calculated to maintain the velocity of the flow of gas from the gas entry point thereto, to the outer extremity or gas ignition point thereof, for the purpose of preventing ignition of the gas in or through the said spreading and directing passage.

These and further objects are achieved by means of the apparatus illustrated in the accompanying drawings, in which:

Figure 1 is a diagrammatic sectional elevation of a burner, showing the invention attached or suspended above a jet housing having a jet and connected to a vapor supply tube having a vaporizing section located above the burner.

Figure 2 is an enlarged cross-sectional view of the burner silencer according to the inven-

tion and showing a portion of the vaporizing section of the vapor supply tube.

Figure 3 is a plan view of part of the burner silencer and vapor supply tube shown in Figure 2.

Figure 4 is a plan view of the part of the burner silencer omitted from Figure 3.

Figure 5 is an enlarged inverted plan view of a portion of the silencer shown in Figure 3, part of the lower wall being broken away.

As seen in Figure 1 there is a saucer 2 in which methylated spirits or the like is ignited to heat the vaporizing tube 3, the jet housing 4, the jet 5 and the burner silencer 6 which is suspended at a selected distance above and concentric with the said jet 5 by means of supporting columns 7 which, in turn, are connected at their lower ends to brackets 8 projecting from the said jet housing 4, and at their upper ends, to adaptors 9 fixed to the said burner silencer 6.

Delivery of oil fuel to the vaporizing tube 3 is effected through an adaptor 10, opposite end of which is internally screw threaded to receive the inlet end of the said vaporizing tube 3, and to which a fuel delivery pipe or the like may be connected.

As seen in Figure 2 the burner silencer 6 comprises a gas directing saucer 11 having a gas entry hole 12 and a gas spreading saucer 13 suspended in the interior of the said gas directing saucer 11 by means of distance pins 14 having seating faces 15. Attached to the seating faces 15 of the distance pins 14 are location pins 16 adapted to project into receiving holes which are situated in the gas directing saucer 11 in the positions indicated also by the numeral 16. The location pins 16 maintain the central positioning of the gas spreading saucer 13 in the gas directing saucer 11 and also allow for easy removal and simple, accurate replacement of the said gas spreading saucer in the event of same being removed for the purpose of cleaning away undesirable or obstructive matter which may fall into or otherwise become lodged in the gas spreading and directing passage in the course of operation.

Also shown in Figure 2 is an air chamber 17 above which is suspended, by a pillar 23, a metal disc or diaphragm 18 supporting a layer of asbestos or other suitable insulating material 19 retained by a metal washer 20 which is secured by a lock-nut 21 and an extended screw 22 which is received in an internally screw threaded portion of the pillar 23 and is adapted to be used as a handle for the removal of the gas spreading saucer 13.

In operation, oil fuel delivered by pressure through the adaptor 10 to the vaporizer tube 3, is vaporized by heat supplied by ignition of methylated spirits or the like placed in the saucer 2 and is delivered in vapor form through the jet 5 after which a calculated proportion of air is induced to mix with the fuel vapor to form a combustible gas which is directed by means of the said jet 5 through the entry hole 12 to strike the gas spreading saucer 13 which, in turn, spreads the gas laterally and upwardly through the gas spreading and directing passage 24 which extends from the gas entry hole 12 to the mouth or outer extremity 29, and is indicated in Fig. 3 by numerals 27 and 28. Upon reaching the mouth or upper extremity 29 of the said gas spreading and directing passage 24, the gas is ignited and forms a circular flame.

A portion of the flame is utilized to heat a vaporizing section 25 of the vaporizing tube 3 and continues vaporization of the fuel after exhaustion of the methylated spirits flame.

5 Explaining further, the gas, after entry to the gas spreading and directing passage 24, is forced passed a series of distance pins 14 which are oval shaped and situated, as better seen in Figure 5, to effect a minimum of deflection to the 10 said gas whilst providing ample support for the gas spreading saucer 13.

Divisions of the flow of gas caused by the distance pins 14, are substantially closed by a slight circumferential restriction 26.

15 The peripheral areas 27 of the gas passage 24 where the volume of passing gas is reduced by the distance pins 14, are slightly narrowed as seen in Figures 2, 3 and 5, to maintain velocity of the reduced volume of gas passing in the said 20 areas 27.

The peripheral areas 28 of the gas passage 24, where the flow of gas is not reduced, are tapered outwardly or widened from the slight circumferential restriction 26 to the mouth or outer

25 extremity 29 of the said gas passage 24 to slightly reduce the velocity of the gas passing therethrough and to allow for expansion of the gas which occurs as the said gas nears the mouth or outer extremity 29.

30 An even velocity of the gas at the mouth or outer extremity 29, is maintained by narrowing and widening the gas spreading and directing passage 24 in the abovementioned manner.

The silencing means of the invention operates 35 in sharp contrast to those used previously, as the velocity of the gas is not accelerated, or the flow of gas is not restricted for acceleration purposes, at the outer extremity or mouth of the gas spreading and directing passageway which also 40 presents no acute restriction to the flow of gas after the gas is delivered therein.

One practical example of a burner silencer constructed according to the principal features 45 of the invention, substantially as illustrated in the drawings, and embodying a means of insulation as described, is as follows:

The gas entry hole diameter was $\frac{1}{8}$ of an inch and the gas spreading saucer was evenly spaced $\frac{7}{64}$ of an inch apart from the gas directing saucer, except at the circumferential restriction 50 where the distance between the saucers was reduced to $\frac{3}{32}$ of an inch. In the areas of the passage formed between the saucers, where the flow of gas was uninterrupted by the distance pins 55 the said passage was tapered outwardly so that the saucers were spaced $\frac{7}{64}$ of an inch apart at the mouth. In those areas of the passage formed between the saucers, where the flow of gas was divided by the distance pins and where

60 a subsequent lesser volume of gas resulted, the distance between the saucers was gradually reduced to $\frac{5}{64}$ of an inch at those areas of the mouth of the passage, where a comparatively even velocity of the gas resulted. The oval distance pins used to space the saucers apart were $\frac{3}{32}$ of an inch wide and $\frac{7}{16}$ of an inch long and were situated as shown in the accompanying drawings. The gas spreading saucer had a diameter of $3\frac{1}{8}$ inches at the annular mouth of

65 the gas passage and the said gas spreading saucer was spaced $1\frac{1}{4}$ inches from a discharge jet having an orifice diameter of 0.022". Kerosene fuel vapour was delivered to the jet at two and one half pounds per square inch and the burner 70 functioned favourably under the conditions of

burning previously referred to, and produced a thermal output of approximately 12,000 British thermal units per hour.

Having now fully described and ascertained my said invention and the manner in which it is to be performed, I declare that what I claim is:

1. In a vapor-burner, a vaporizing tube for liquid fuel, a silencing device comprising upper and lower spaced apart dished members having their concave sides directed upwardly, the upper member being nested in the lower member to form a vapor-spreading passageway between them ending in an unbroken opening of closed configuration and the lower member having an aperture adapted to receive fuel vapor from the vaporizing tube, and supports for the upper member arranged in the said passageway at spaced intervals around said aperture inwardly from the outer end of said passageway, the walls of said passageway being closer together at positions disposed radially outwards from said supports than at locations between said positions.

2. In a vapor-burner, a vaporizing tube for liquid fuel, a silencing device comprising upper and lower spaced apart dished members having their concave sides directed upwardly, the upper member being nested in the lower member to form a vapor-spreading passageway between them ending in an unbroken opening of closed configuration and the lower member having an aperture adapted to receive fuel vapor from the vaporizing tube, and supports for the upper member arranged in the said passageway at spaced intervals around said aperture inwardly from the outer end of said passageway, the walls of said passageway being closer together at positions disposed radially outwards from said supports than at locations between said positions, and the walls of said passageway diverging outwardly at said locations from a circumferential constriction in said passageway disposed outwardly of said supports.

3. In a vapor-burner, a vaporizing tube for liquid fuel, a silencing device comprising upper and lower spaced apart dished members having their concave sides directed upwardly, the upper member being nested in the lower member to form a vapor-spreading passageway between them ending in an unbroken opening of closed configuration and the lower member having an aperture adapted to receive fuel vapor from the vaporizing tube, and pins projecting from the lower face of the upper member at spaced intervals around said aperture inwardly from the outer end of said passageway and adapted to seat in sockets in the lower member, the walls of said passageway being closer together at positions disposed radially outwards from said pins than at locations between said positions.

4. In a vapor-burner, a vaporizing tube for liquid fuel, a silencing device comprising upper and lower spaced apart dished members having their concave sides directed upwardly, the upper member being nested in the lower member to form a vapor-spreading passageway between them ending in an unbroken opening of closed configuration and the lower member having an aperture adapted to receive fuel vapor from the vaporizing tube, a layer of heat-insulating material covering an air space in the base of the upper member, and supports for the upper member arranged in the said passageway at spaced intervals around said aperture inwardly from

the outer end of said passageway, the walls of said passageway being closer together at positions disposed radially outwards from said supports than at locations between said positions.

5. In a vapor-burner, a vaporizing tube for liquid fuel, a silencing device comprising upper and lower spaced apart dished members having their concave sides directed upwardly, the upper member being nested in the lower member to form a vapor-spreading passageway between them ending in an unbroken opening of closed configuration and the lower member having an aperture adapted to receive fuel vapor from the vaporizing tube, a layer of heat-insulating material covering an air space in the base of the upper member, and pins projecting from the lower face of the upper member at spaced intervals around said aperture inwardly from the outer end of said passageway and adapted to seat in sockets in the lower member, the walls of said passageway being closer together at positions disposed radially outwards from said supports than at locations between said positions and the walls of said passageway diverging outwardly at said locations from a circumferential constriction in said passageway disposed outwardly of said supports.

6. In a vapor-burner, a vaporizing tube for liquid fuel, a silencing device comprising upper and lower spaced apart dished circular members having their concave sides directed upwardly, each member having a substantially flat central portion and an outwardly and upwardly sloping peripheral portion, the upper member being nested in the lower member to form a vapor-spreading passageway between them ending in an unbroken opening of closed configuration and the lower member having an aperture adapted to receive fuel vapor from the vaporizing tube, a circular layer of heat-insulating material covering an air-space defined by the central portion and the lower part of the peripheral portion of the upper member, and upper-member-supporting pins projecting downwardly from the central portion of the upper member at spaced intervals around said aperture, the walls of said passageway formed by the peripheral portions of the said members being closer together at positions disposed radially outwards from said pins than the walls of said passageway at locations between said positions and the width of said passageway between said positions increasing outwardly in the peripheral portions of the said members, the said passageway also being constricted at the base of the said peripheral portions.
